UNITED STATES PATENT OFFICE.

WINZEL W. THOM, ALEXANDER S. T. LAGAARD, AND ALBERT M. WALZER, OF MINNEAPOLIS, MINNESOTA; SAID THOM AND SAID LAGAARD ASSIGNORS TO SAID WALZER.

DESIGN FOR A GAME BOARD.

Application filed July 30, 1927. Serial No. 22,964. Term of patent 14 years.

To all whom it may concern:

Be it known that we, WINZEL W. THOM, ALEXANDER S. T. LAGAARD, and ALBERT M. WALZER, all citizens of the United States, residing at Minneapolis, in the county of Hennepin and State of Minnesota, have invented a new, original, and ornamental Design for Game Boards, of which the following is a specification, reference being had to the accompanying drawing, forming part thereof.

The figure is a perspective view of a game board illustrating our new design arranged lengthwise upon the sheet of drawings.

We claim:

The ornamental design for a game board, as shown.

WINZEL W. THOM.
ALEXANDER S. T. LAGAARD.
ALBERT M. WALZER.
